UNITED STATES PATENT OFFICE.

ALVA M. DOW, OF BRAINTREE, MASSACHUSETTS.

WASHING-MACHINE.

1,362,240.

Specification of Letters Patent. Patented Dec. 14, 1920.

Application filed June 2, 1919. Serial No. 301,209.

To all whom it may concern:

Be it known that I, ALVA M. Dow, a citizen of the United States, residing at Braintree, county of Norfolk, State of Massachusetts, and whose post-office address is 46 Lemoyne street, Braintree, Massachusetts, have invented an Improvement in Washing-Machines, of which the following description, in connection with the accompanying drawings, is a specification, like characters on the drawings representing like parts.

This invention relates to a washing machine and the object of the invention is to provide a simple and efficient machine of this character which will insure the washing of the clothes in a thorough manner without injury thereto.

The object of the invention is further to provide a machine in which the tub containing the clothes shall be unobstructed at the interior so that nothing shall come into contact with the clothes to injure or tear them and in which the washing or cleansing operation shall be performed by the water or cleansing fluid being brought into intimate contact with the clothes as they slide along the sides and are tossed or thrown from one side to the other of the interior of the tub.

The object of the invention is further and more specifically to provide a tub having substantially the shape of a rectangular parallelepiped mounted to rotate upon an axis passing through to opposite sides of the tub at points similarly disposed to but at opposite positions with respect to the centers of the said sides whereby during the rotation of the tub the clothes will be thrown back and forth from one flat side of the tub to another and slid back and forth along the sides and thus thoroughly shaken up and brought into contact with the cleansing fluid.

The object of the invention is further to provide a tub of the foregoing character in which the sides and particularly those sides through which the axis of rotation does not pass are reticulated as by being formed of spaced slats so that as the tub is rotated partially immersed in a tank of water or cleansing fluid the fluid will be splashed and sucked into and out of the tub and into and out of contact with the clothes.

The object of the invention is further to

provide a washing machine having a pump connected with the tank by means of which the water or cleansing fluid may readily be removed from the tank. 55

The object of the invention is further to provide a washing machine having a tank 60 containing a rotating tub, a wringer, a pump for removing the cleansing fluid from the tank, a motor or other driving element, and means for independently connecting either the tub, the wringer, or the pump or any 65 combination thereof to said motor or driving element so that either may be operated independently or in any desired combination.

These and other objects and features of 70 the invention will appear more fully from the accompanying description and drawings and will be particularly pointed out in the claims.

The drawings illustrate a type of washing machine designed for household use embodying a preferred form of the invention. 75

In the drawings:

Figure 1 is a side elevation of a washing machine embodying the preferred form of 80 85 the invention.

Fig. 2 is a front elevation of the machine shown in Fig. 1.

Fig. 3 is a detail in vertical transverse section showing the connection between the 85 driven shaft and the tub.

Fig. 4 is a view in vertical cross section enlarged and partially broken away taken on the line 4-4 of Fig. 2.

Fig. 5 is a view in side elevation of the 90 tub with the interior outline of the tank indicated in dotted lines.

Fig. 6 is a front elevation of the tub with the interior outline of the tank indicated in dotted lines. 95

The main elements of the washing machine are supported upon a frame which may be constructed in any suitable manner and is herein shown as chiefly composed of angle irons. The frame is shown comprising four vertical uprights 1 which may be provided with casters 2, a series of transverse struts 3 located a short distance from the lower ends of the uprights and securing them together. A pair of struts 4 at the 100 sides of the frame connecting the uprights 1 at the top, a pair of uprights 5 connecting the struts 3 and 4 at each side of the frame, 105

a pair of struts 6 extending at the sides of the frame between the struts 1 at the bottom, and a bed plate 7 mounted on the struts 6 and having an extension 8 projecting at 5 one side of the frame.

The tank for containing the water or cleansing fluid is preferably made of sheet metal and extends between the top of the frame and the struts 3. This tank 9 has its 10 sides preferably of U shape so as to present a semi-cylindrical shape at the bottom.

A suitable cover 10 for the tank is provided and mounted to slide into place at the top of the frame.

15 The tub, a preferred form of which is shown in detail in Figs. 5 and 6 where the outline of the tank is indicated in dotted lines, is substantially in the form of a rectangular parallelepiped. That is to say, 20 each of its six sides forms a substantial rectangle. Preferably the tub is substantially in the form of a cube. The term "substantially" is used because it is desirable to slab off four of the corners of the tub as illustrated 25 and thus without materially altering the capacity of the tub enable a smaller tank to be employed.

The axis of rotation of the tub passes through bearings on two of the opposite 30 sides of the tub at points similarly disposed but in opposite positions with respect to the centers of the said sides. Thus as the tub is rotated the clothes in the interior of the tub slide along the sides and are thrown or 35 dropped from one side to the other and thoroughly agitated. This peculiar method of operation by which the clothes are forced to slide back and forth in the direction of the axis of rotation and by which the clothes 40 are thrown or dropped from one flat side to another of the six sides of the tub prevents the clothes from becoming balled up or assuming any particular position in the tub and insures the thorough and intimate contact 45 of the water or cleansing fluid with all parts of the clothes.

All of the six sides of the tub, but in any event the four sides upon which the bearings are not located, are reticulated to enable the 50 water in the tank to be sucked or splashed in and out of the tub as the tub is rotated in the tank.

In the preferred construction illustrated 55 all the six sides of the tub are formed of transverse slats 11 slightly separated to provide spaces 12 and each slat is further provided at regular intervals with small cylindrical apertures 13. These apertures 13, as clearly shown in the portion of the tub at 60 Fig. 5, are counter-sunk in the interior and preferably at the exterior also. This counter sinking of the ends of the apertures 13 insures the ready passage of the water back and forth therethrough and also prevents 65 any rough edges at the interior to catch or

injure the clothes. The slats 11 may be and preferably are formed of wood and are secured to a suitable interior framework.

As already pointed out four of the corners of the tub are slabbed off as shown in Fig. 6 70 to enable the tank to be somewhat reduced in size without materially altering the capacity of the tub.

Bearing plates 14 are secured to the opposite sides and provided with journal 75 sockets 15 and are so mounted that the journal sockets 15 extend from points similarly disposed but at opposite positions with respect to the centers of these sides. That is to say, in the preferred form illustrated, the bearing plate 14 with its socket 15 at the right hand side in Fig. 5 is at a given distance below the center of that side where the corresponding opposite bearing plate is at the same distance above the center of its 85 side. This arrangement brings the axis of rotation parallel to two of the sides and reduces the space occupied by the tub in its rotation but any desired points for the location of the bearing plates may be selected 90 within the broader scope of the invention so long as the axis of rotation passes through to opposite sides of the tub at points similarly disposed to but at opposite positions with respect to the centers of the said sides. 95

The sockets 15 contain bearing studs 16 and 17 respectively held in place in the sockets by pins 18. These bearing studs are seated in open mouth bearings formed in the bearing members 19 mounted at the interior 100 of the tank and extending transversely between and secured through the tank to the uprights 5. It will thus be seen that the tub with its bearing studs can be lifted from the open mouth bearings 19 and removed 105 from the tank when required for repair or cleansing.

The operation of the tub, of the wringer, and of the pump already referred to may be secured from any suitable source of power, 110 but preferably the machine is provided with a motor such as an electric motor 20 mounted on the bed plate 7 and driving a shaft 21. Electric connections are indicated at 22 at a convenient point near the top of the tub and 115 the wires, not shown, extend down the framework therefrom to the motor.

The tank is provided at the bottom with an outlet 23 controlled by a hand valve 24 and connected with a pipe or hose 25. A 120 pump 26 which may be of any suitable character is mounted on the bed plate 7 and connected at 27 with the pipe or hose 25. A clutch 28 maintained closed by the helical spring 29 and opened by pulling on the 125 rod 30 enables the pump to be connected to and disconnected from the motor when desired. A suitable catch locks or frictionally holds the clutch in open position. This arrangement enables the water or 130

cleansing fluid in the tank to be readily removed and discharged at any convenient point and eliminates the necessity of connecting the machine to a sewerage system 5 or of draining the water or cleansing fluid off and carrying it away from the machine.

The machine also is provided with a wringer which may be of any suitable type. As shown, the wringer comprises a suitable 10 frame 31 in which are mounted the wringer rolls 32 and 33. The wringer frame is securely bolted or secured to a bracket 34 and the wringer frame is preferably arranged as shown in an inclined position so 15 that as the clothes are taken from the tub they feed downwardly between the wringer rolls and are thus easily drawn in between the rolls and discharged downwardly into a suitable receptacle.

20 The mechanism for operating the tub and the wringer is mounted at the exterior and at one side of the frame and all the working parts are inclosed in a metal casing. A split metal sleeve 35 is rigidly secured to transverse supports 36 extending between the uprights 5 and this split sleeve is clamped and unclamped by a screw operated by a handle 37. The gear casing 38 is secured thereto, or is cast integral with, the wringer supporting bracket 34 and is provided with a shoul- 25 dered sleeve 39 passing down into the split sleeve 35. Thus when the split sleeve is clamped upon the sleeve 39 the gear casing 38 with the bracket 34 and the wringer is 30 rigidly held in place and at the same time means are thus provided for adjusting the wringer at any desired horizontal angle.

From the split sleeve 35 a shaft casing 40 extends downwardly to the tub gear casing 41 which is rigidly secured to transverse supports 37 extending between the uprights 5 from the gear casing 41. The shaft casing 40 continues on down to the gear casing 42 mounted on supports 43 from the bed plate 45 7. A vertical shaft 44 extends up through the gear casings 42, 41 and 38 and the shaft casing 40. This vertical shaft 44 at its lower end is provided with a worm wheel 45 in engagement with and driven by a worm 50 46 mounted on the shaft 21. The shaft 21 is preferably formed in two sections united by a rubber coupling 47 to take up any sudden shock or jar.

It will thus be seen that when the motor 55 is in operation the shaft 44 is continuously operated in one direction.

In the gear casing 41 the shaft 44 is provided with a beveled gear 48 loosely mounted thereon and journaled in the gear casing. 60 A sleeve 49 is splined to the shaft 44 in the gear casing 41 and provided with an exterior operating handle 50. This sleeve 49 is provided with a projection 51 adapted to seat in a corresponding recess in the beveled gear 48 so that by operating the handle 50

the beveled gear may be clutched to or unclutched from the shaft 44. The beveled gear 48 meshes with a beveled gear 52 in the gear casing 41 secured to the horizontal stud shaft 53 which extends through 70 the gear casing 41 and engages by separable joint connections 54. The end of the bearing stud 16 which as already explained is secured to the tub. Thus, by operating the handle 50 the tub is connected to or disconnected from the shaft 44 as desired.

At the upper end the wringer roll 32 is provided with a shaft extending into the gear casing 38 and carrying a beveled gear 55 in mesh with oppositely disposed beveled gears 56 and 57 loosely mounted on the shaft 44. A collar 58 is splined to the shaft 44 between the beveled gears 56 and 57 and is provided with projections 59 adapted to fit in corresponding recesses in the opposed 85 beveled gears. This collar is connected to a rack 60 operated by a pinion 61 secured to a handle 62 on the exterior of the gear casing 38. Consequently by moving the handle 62 in one direction or the other the collar 58 90 will be connected to one or the other of the beveled gears 56 and 57 and the rotation of the wringer rolls secured in either direction desired. When the wringer is not in use the collar 58 is moved into the neutral position 95 shown in Fig. 4.

It will thus be seen that by operating the push rod 30 the handle 50 and the handle 62, either the pump, the tub, or the wringer may be connected to the driven shaft, each 100 independently of the other, or in any combination as desired.

In the operation of the machine, the cover 10 of the frame is removed and the clothes placed in the tub. For this purpose 105 the tub is provided with a suitable door shown as composed by hinging a group of the slats at 63 and this cover is maintained closed as by suitable turn buttons 64. After the clothes have been placed in the tub the 110 tank is partially filled with water preferably to a level somewhat below the axis of rotation, the cover 10 is replaced, the handle 50 is pushed downwardly to clutch the tub to the driving shaft, and the motor started. 115 As the tub revolves its flat sides slap against the water in the tank forcing the water in and out between the slats and through the apertures 13 and at the same time the clothes are thrown and tossed about from one side 120 of the tub to the other and slid back and forth along the sides in the direction of the axis of rotation. Thus the water or cleansing fluid is brought into intimate contact with all portions of the clothes as it is sucked 125 back and forth through the tub.

After the operation has been continued a sufficient length of time the handle 50 is pulled upwardly disconnecting the wringer from the driving shaft, the cover 10 is re- 130

1 moved, the tub opened and the clothes are ready to be fed to the wringer. The handle 62 is now moved to cause the wringer rolls to rotate and the clothes are fed to the 5 wringer. If the clothes stick, or if for any reason it is desired to feed the clothes in the opposite direction, the handle 62 is swung in the opposite direction causing a reverse rotation of the wringer rolls. After the 10 clothes have been wrung out the wringer is disconnected from the driving shaft by operating the handle 62 to bring the collar to neutral position. The water is then removed from the tank by pushing on the 15 handle 30 to clutch the motor to the pump and pump the water out. Rinsing operations may be formed by filling the tank with fresh water and repeating the operation.

Having thus described my invention what 20 I claim as new and desire to secure by Letters Patent is—

1. A washing machine comprising a tank for the cleansing fluid, a tub inclosed within the tank and having substantially the shape 25 of a rectangular parallelepiped having some of its sides reticulated and mounted to rotate on an axis extending through opposite sides at points similarly disposed to but at opposite positions with respect to the 30 centers of said sides whereby when the tank is partly filled and the tub partly immersed in the cleansing fluid the articles being cleansed will during rotation of the tub slide along the sides and be periodically lifted by the 35 sides of the tub successively and dropped into the fluid and whereby the water in the tank will be forced back and forth through the reticulations into and out of contact with the articles.

40 2. A washing machine comprising a tank for the cleansing fluid, a tub inclosed within the tank and having substantially the shape of a rectangular parallelepiped having some of its sides reticulated and 45 mounted to rotate on an axis extending through opposite sides at points similarly disposed to but at opposite positions with

respect to the centers of said sides and extending in parallelism with two of the other sides, and means for rotating the tub partly 50 immersed in the cleansing fluid on its axis to cause the articles being cleansed to slide along the sides in the direction of the axis of rotation and to fall successively against all six sides of the tub and to cause the 55 water in the tank to be forced back and forth through the reticulations into and out of contact with the articles.

3. A washing machine comprising a tub having substantially the shape of a rectangular parallelepiped, a tank inclosing the tub and adapted to hold cleansing fluid sufficient for the partial immersion of the tub, journal bearings between the tank and tub on the exterior of opposite sides of said 60 tub projecting along an axis at points similarly disposed to but at opposite positions with respect to the centers of the said sides with the axis of rotation extending in parallelism with two of the other sides, and having the four sides from which said bearings do not project reticulated whereby when the tank is partly filled and the tub partly 65 immersed in the cleansing fluid the articles being cleansed will during rotation of the 70 tub slide along the sides in the direction of the axis of rotation and be periodically lifted by the sides of the tub successively and dropped into the fluid.

4. A washing machine comprising a 80 frame, a tank for the cleansing fluid supported by said frame, a tub mounted for rotation in the tank, a motor mounted on the frame, a pump mounted on the frame connected to the tank and acting when operated 85 to remove the cleansing fluid from the tank and enable it to be discharged upward against the force of gravity, and means for connecting to and disconnecting from the motor either the tub or the pump.

In testimony whereof, I have signed my name to this specification.

ALVA M. DOW.
